SASH HOLDER

Laurence Francis Moroney, Moonee Ponds, near
Melbourne, Victoria, AustraliaApplication October 8, 1938, Serial No. 234,028
In Australia January 24, 1938

10 Claims. (Cl. 292—73)

This invention relates to improvements in fittings for vertically slideable window-sashes, shutters or the like (hereinafter, for brevity, termed "window sashes"), whereby the same can be conveniently moved upwards and downwards and automatically held in selected positions and thereby dispense with sash-balancing weights, pulleys, cords and window frames having boxes for said weights as are now required with conventional window constructions.

A principal object of the invention is to provide a holding device for a vertically sliding window sash, which is of neat, strong and durable construction, capable of being economically manufactured and readily fitted, and in operation will be found to be reliable and efficient by permitting the window sash to be conveniently raised and lowered and rigidly sustained in any required vertical position.

A further object is to provide a holding device for a vertically sliding window sash, which device has a gripping roller associated with a spring-actuated braking element so constructed and arranged that the roller is wedged against the side of the sash stile and thus firmly retains it in position, means being provided to regulate the pressure exerted by the roller whereby the device is adaptable for window sashes which differ in weight.

A still further object is to provide a holding device for a window-sash, which will also prevent rattling of the sash in any position to which it has been vertically adjusted, and having means whereby the sash can be restrained against movement in either direction, thereby functioning additionally as a window lock.

According to the invention, I provide a casing adapted to be fitted into a mortise formed in a side member of a window frame. Housed within this casing is a roller which normally projects outwardly therefrom to press against the side of the sash stile. Bearing against the periphery of the roller is a pivoted element which is acted upon by a spring, the compressional force of which can be conveniently regulated so that said element while impelling the roller also acts as a brake thereon. The casing has guides for the roller axle so formed that upward movement imparted to the window sash rotates the roller and causes it to be retracted within the casing against spring pressure. When the window sash is released, the roller is automatically impelled to be wedged against the sash stile, thereby sustaining the window sash in the vertical position to which it has been moved.

The invention is illustrated by the accompanying drawings, to which reference is now made for the purpose of a detailed description.

Fig. 1 is a side elevation of the holding device.
Fig. 2 is a front elevation of the same.

Fig. 3 is a vertical section on the line 3—3 of Fig. 2.

Fig. 4 is a side sectional elevation of the casing which houses the roller, showing oblique guide grooves for the roller axle.

Fig. 5 is a side sectional elevation of the casing showing the roller in the retracted position it assumes when the window sash is being moved vertically upwards.

Fig. 6 is a perspective view of the tensioning plate.

Fig. 7 is a similar view of the braking plate.

Fig. 8 is a perspective view of the casing which houses the roller.

Fig. 9 is a view of the roller having a fixed axle.

Fig. 10 is a fragmentary view of a roller having an axial hole in the ends of which are fitted hardened balls to provide a frictionless axle.

Fig. 11 is an assembly view illustrating the sash holding device mounted in operative position on a window frame.

Fig. 12 is a side sectional view showing one means for applying the invention to a double-hung window.

In these views 1 designates an open-ended casing consisting of a base 2 and two vertical spaced walls 3 and having at its front end upper and lower vertical flanges 4 and 5, respectively. The said casing with its flanges may be conveniently constructed of metal by die-casting operations.

Housed within the casing 1 is a solid roller 6 which normally projects through the front of said casing and is adapted to bear against the side of a stile of a vertically sliding window sash indicated by S. This roller may have a fixed axle as 7 or, alternatively, it may be formed with an axial hole 8 at the opposite ends of which are fitted hardened balls 9 which project laterally from said roller—see Fig. 10—and function as a rotatable frictionless axle. The space between said balls may be filled with grease to provide a self lubricating axle for said roller.

Guide grooves 10 are formed obliquely in the opposed faces of the vertical walls 2 and they extend from points adjacent to the front of said casing to the upper part thereof. These grooves accommodate the ends of the roller axle 7, and if a roller having hardened balls 9 as shown in Fig. 10 be used, said grooves are of semi-circular configuration in cross section.

A tensioning plate 11 is pivotally and detachably fitted within the casing 1 at the rear portion thereof. This plate has at its lower end a hook-shaped lug 12 which is passed through an elongated slot 13 formed in the casing base 2 and engages a recess 14 on the underside of said base. The tensioning plate has at its upper end an off-set member 15 wherein a hole 16 is formed to receive the inner end of a horizontal bolt 17 which is inserted through a countersunk hole 18 in the upper flange 4. The bolt has a screw head 19 which is accommodated in said countersunk hole, and fitted on its rear end is a nut 20 that is restrained against rotation on the bolt by a lip 21 projecting from said off-set member and abutting against said nut.

A braking plate 22 is pivotally and detachably secured at its rear end to the tensioning plate 11 and it bears evenly upon the periphery of the roller 6. The pivotal connection between the braking plate and the tensioning plate is effected by forming on the rear end of the braking plate a hook-shaped extension 23 which is passed through and is engaged by an elongated slot 24 formed in the tensioning plate above the pivot point of the latter.

A stout compression spring 25 extends between the upper end portions of the tensioning plate 11 and the braking plate 22, being maintained in operative position by studs 26 and 27 on the opposed faces of said plates. This spring causes the plate 11 to exert pressure upon the roller 6, and such pressure can be conveniently regulated by applying a screw-driver to the screw-head 19 of the bolt 17 to rotate the latter and impart pivotal movement in the required direction to the tensioning plate 11.

A mortise is made in the side member of a window framing W to snugly receive the casing 1 and its vertical flanges 4 and 5, which latter are flush with the window framing as shown in Fig. 11. A fastening screw 28 is passed through a countersunk hole 29 in the lower flange 5 of the casing 1 into the window framing to prevent displacement of the holding device, which is preferably positioned at or about the midpoint of a double-hung window so that the screw-head 19 of the bolt 17 is conveniently accessible to regulate the spring pressure when the window sash is moved to its lowermost position.

The roller 6 is preferably constructed of metal, and the tensioning plate 11 and the braking plate 22 may conveniently be made of metal by die-casting operations for accurate and economical production.

For light window-sashes, only one holding device may be provided, but for general application to windows including those having heavy window sashes, I prefer to use two of the holding devices for each sash, the same being fitted and fastened to opposite side members of the window frame W in corresponding locations. The spring-actuated rollers 6 of said holding devices will thus bear against corresponding parts of the stiles of the sliding sash and ensure desired evenness of action being obtained when the sash is being raised or when it is being lowered.

When the window sash is being raised, the roller 6 which bears against the side of the sash stile is rotated, and the lifting pressure applied to the sash causes said roller to be retracted within its casing 1. The roller is guided upwardly and rearwardly within said casing by the oblique grooves 9 wherein the roller axle is fitted, such movement being against the regu-

lated pressure of the spring-influenced braking plate 22—see Fig. 5. By reason of the retraction of the roller and the consequential reduction of the pressure which it exerts on the sash stile, the window sash can be raised with but little effort.

When the window sash is released, the roller 6 is forced downwardly and outwardly by the increased spring pressure which is now exerted on it through the braking plate 22. Said roller grips the side of the sash stile in wedge fashion, sustaining the sash rigidly in its elevated position and in such manner as will effectively prevent rattling of the sash.

To close the window sash sufficient downward force is applied thereto to overcome the lateral pressure exerted by the roller 6, impelled by spring pressure, upon the sash stile, and in this closing action said roller is constantly rotating.

When it is desired to lock the window sash against vertical movement, the bolt 15 is rotated by the use of a screw-driver applied to its head 18 until the force applied by the spring 25, acting through the braking plate 22, upon the roller 6 is sufficient to prevent rotation of said roller and also its inward and upward movement within the casing 1. By this means, the window-sash can be conveniently locked in closed position, and it cannot be moved therefrom until the bolt 15 is rotated in the opposite direction to reduce the compressional force of the spring 25 and thus release the roller from the considerable braking pressure exerted thereon by said braking plate.

What I do claim is:

1. Means for sustaining slidable window sashes comprising a casing adapted to be fitted within a mortise in a side member of a window frame, a roller having an axle and mounted in said casing adapted to exert gripping pressure on the sash stile and to be retracted within said casing upon upward movement of the sash, guides in said casing for said axle, a braking element pressing upon said roller, a spring exerting pressure on said braking element, and means for regulating the pressure of said spring.

2. Means for sustaining slidable window sashes comprising a casing adapted to be fitted within a mortise in a side member of a window frame, a roller having an axle and mounted in said casing adapted to exert gripping pressure on the sash stile and to be retracted within said casing upon upward movement of the sash, guides in said casing for said axle, a movable tensioning plate connected to said casing, a braking plate connected to said tensioning plate and pressing upon said roller, a spring between said tensioning plate and said braking plate, and means for adjusting said tensioning plate to regulate the pressure exerted by the spring on said braking plate.

3. Means for sustaining slidable window sashes comprising a casing adapted to be fitted within a mortise in a side member of a window frame, a spring-actuated roller having an axle and mounted in said casing adapted to exert gripping pressure on the sash stile and to be retracted within said casing upon upward movement of the sash, and obliquely disposed guide grooves in said casing accommodating said axle.

4. Means for sustaining window sashes according to claim 1, wherein said roller is provided with an axial hole and hardened balls fitted in the opposite end of said hole providing a frictionless axle for said roller, and wherein

said guides for said axle comprise grooves of semi-circular configuration formed in the vertical walls of the casing.

5. Means for sustaining window sashes according to claim 1, wherein the guides for said roller axle comprise grooves formed obliquely in the vertical walls of the casing which houses said roller.

6. Means for sustaining slidable window sashes comprising a casing adapted to be fitted within a mortise in a side member of a window frame, a roller having an axle and mounted in said casing adapted to exert gripping pressure on the sash stile and to be retracted within said casing upon upward movement of the sash, guides in said casing for said axle, a tensioning plate pivoted to said casing, a braking element connected at one end to said tensioning plate and acting upon said roller, a compression spring between said tensioning plate and said braking plate, and means for adjusting said tensioning plate to regulate the compressional force of said spring.

7. Means for sustaining slidable window sashes according to claim 6, wherein said tensioning

plate is pivotally connected at its lower end to the base of the casing and the braking plate is pivotally connected at its rear end to said tensioning plate.

5 8. Means for sustaining slidable window sashes according to claim 6, wherein the braking element comprises a plate pivotally and detachably connected at its rear end to said tensioning plate and has its free end portion bearing on the periphery of said roller.

10 9. Means for sustaining slidable window sashes according to claim 6 wherein said casing is formed with vertical flanges at its forward end, and said tensioning plate is adjusted by a bolt 15 passed through one of said flanges and through said tensioning plate.

10 10. Means for sustaining slidable window sashes according to claim 6, wherein said tensioning plate is formed with an off-set member at its upper end, a bolt having a screw-head passing from the front of the casing through said off-set member and fitted with a nut, and a lip on said off-set member abutting against said nut to restrain the nut against rotation.

LAURENCE FRANCIS MORONEY.
